(57) **CLAIM**

We claim the ornamental design for the electronics interface housing for luggage, as shown and described.

DESCRIPTION

FIG. 1 is a right perspective view of an electronics interface housing for luggage.

FIG. 2 is a left perspective view of the housing of FIG. 1.

FIG. 3 is left side view of the housing of FIG. 1.

FIG. 4 is a front view of the housing of FIG. 1.

FIG. 5 is a right side view of the housing of FIG. 1.

FIG. 6 is a rear view of the housing of FIG. 1.

FIG. 7 is a top view of the housing of FIG. 1.

FIG. 8 is a bottom view of the housing of FIG. 1; and,

FIG. 9 is right perspective view shown in a position of use. In all figures, broken lines illustrate environmental structures and form no part of the claimed design.
